[57] **CLAIM**

The ornamental design for a pendulum for clock, as
shown and described.

DESCRIPTION

FIG. 1 is a front elevational view of a pendulum for
clock showing my new design;

FIG. 2 is a rear elevational view thereof;

FIG. 3 is a right side elevational view thereof, the left
side being the same in appearance as the right side;

FIG. 4 is a top plan view thereof; and,

FIG. 5 is a bottom plan view thereof.

FIG. 1

FIG. 3

FIG. 2

FIG. 4

FIG. 5
